SONIC FISH DETECTOR

Jan A. Van Den Broek, Ann Arbor, and George W. Toma, Dexter, Mich., assignors to Transidyne General Corporation, Ann Arbor, Mich.

Filed June 1, 1971, Ser. No. 149,120

Term of patent 14 years

Int. Cl. D10—04

U.S. Cl. D26—1 Q

FIG. 1 is a left side elevational view of a sonic fish detector showing our new design, the opposite side being a mirror image thereof;

FIG. 2 is a front elevational view thereof; and

FIG. 3 is a rear elevational view thereof.

We claim:

The ornamental design for a sonic fish detector, as shown and described.
